Application May 22, 1956, Serial No. 586,547

12 Claims. (Cl. 200—116)

This invention relates to thermostatic switches, and more particularly, to thermostatic switches which are controllable manually in conjunction with thermostatic control thereof.

This invention represents an improvement over the invention disclosed and claimed in United States Letters Patent 2,345,451, granted March 28, 1944, to J. D. Bolesky. In addition to the advantages provided by the invention set forth in that patent, the present invention provides additional advantages thereover and obviates certain disadvantages thereof as will become apparent as the description proceeds.

Accordingly, an object of the present invention is to provide a thermostatic switch which provides the advantages set forth in the above-mentioned patent and, in addition, which represents an improvement over the invention presented thereby.

A further object of this invention is to provide a thermostatic switch having improved translation of forces to the thermostatic means.

A further object of this invention is to provide a thermostatic switch by which localized deformation of the thermostatic means is substantially eliminated or greatly reduced.

A further object of the invention is to provide a thermostatic switch which is more easily and more accurately calibrated.

A further object of this invention is to provide an improved thermostatic switch embodying thermostatic means upon which wear is substantially reduced thereby prolonging the useful life of the switch.

Among further objects of this invention are the provision of a thermostatic switch which is compact, which has improved shock and vibration resistant characteristics, which embodies a minimum number of parts, which is simple and economical to assemble and manufacture, and which is readily adapted for modification to alter the movement of the contacts thereof to closed position.

Other objects will be in part obvious and in part pointed out hereinafter.

The invention accordingly comprises the elements and combination of elements, features of construction, and arrangement of parts which will be exemplified in the structures hereinafter described; and the scope of the application of which will be indicated in the following claims.

In the accompanying drawings, in which are illustrated several of various possible embodiments of the invention;

Fig. 1 is a plan view of a switch embodying the present invention;

Fig. 2 is a sectional view taken along line 2—2 in Fig. 1;

Fig. 3 is a sectional view taken along line 3—3 in Fig. 2;

Fig. 4 is a view similar to Fig. 1 but with the cover and actuating means removed;

2

Fig. 5 is a view similar to Fig. 2 but showing the parts in a different position;

Fig. 6 is a broken view, partly in section, and showing a portion of an actuating means of different form than that shown in Figs. 2 and 5;

Fig. 7 is a side view, partly in section, and showing another switch embodying this invention;

Fig. 8 is a view similar to Fig. 7 but showing certain of the parts thereof in a different relative position;

Fig. 9 is a sectional view taken along line 9—9 in Fig. 7;

Fig. 10 is a perspective view of a sub-assembly of the embodiment shown in Figs. 7 and 8;

Fig. 11 is a fragmentary side view including a thermostatic sub-assembly of different form than that included in Figs. 2 and 7;

Fig. 12 is a fragmentary side view including a thermostatic subassembly of different form than that included in Figs. 2 and 7 and Fig. 11; and

Fig. 13 is a fragmentary view similar to a portion of Fig. 7 but showing the thermostatic element in a different position.

Similar reference numerals indicate like parts throughout the several views of the drawings.

Referring to Figs. 1—5, which illustrate one embodiment of this invention, a base or casing 2 is shown which is formed of a suitable insulating material such as one of the customary molded plastics, ceramics, etc. Base 2 includes a lower base member 4 and an upper base member or cover 6. Base member 4 includes side walls 8, 8 and end walls 10, 10, all of which mate with base member 6. Fixedly carried by base member 4 are electrically conductive terminals 12 and 14, each of which includes a laterally extending portion 16 and 18, respectively. Portion 16 of terminal 12 mounts an electrical contact 20, and portion 18 of terminal 14 mounts an electrical contact 22.

Base member 4 provides a raised boss 24 having a socket 26 therein. A bushing 28 may be fixedly secured in socket 26 as shown in Figs. 2 and 5.

A thermostatic sub-assembly 29 is formed, in part, by thermostatic element 30. Thermostatic element 30 is electrically conductive and snap-acting in response to temperature change. This element may be of the type disclosed in United States Letters Patents 1,448,240 or 2,317,831, or disclosed in copending application Serial No. 497,109, filed March 28, 1955. Reference is hereby made to these disclosures for the details of structure and function of this type of thermostatic element.

An electrical contact 32 is carried by thermostatic element 30 for cooperation with contact 20. Thermostatic element 30 may carry another contact 34 for cooperation with contact 22. It will be clear that one of contacts 32 or 34 could be eliminated depending upon the intended functions of the switch. For example, an insulating piece could be substituted for either of contacts 32 or 34. Alternatively, thermostatic element 30 could be provided with additional contacts.

An aperture 35 is provided in thermostatic element 30 which extends therethrough from one side to the other. As best shown in Figs. 2 and 5, a shank 36 is loosely disposed in aperture 35. Provided on shank 36 is a head 38, the bottom portion of which is engageable with one side of thermostatic element 30. Another portion of head 38 provides a cam or cam surface 39 and a catch adjacent thereto in the form of a depression 40, the purpose of which will become apparent later in this description.

Shank 36 is fastened to a cup-shaped member 42 in any suitable manner such as by staking at 44. Cup-shaped member 42 is telescopically engaged with and guided for movement with respect to base 2 by bushing 28. Means

for biasing thermostatic element 30 upwardly as viewed in Figs. 2 and 5 is provided in the form of a compression coil spring 46 having one end engaged with base 2 and its other end seated in cup-shaped member 42. Compression spring 46 biases thermostatic element 30 for movement along a path from the position with respect to contacts 20 and 22 as shown in Fig. 2 to the relative position shown in Fig. 5. It will be noted that with thermostatic element 30 in the downwardly bowed shape or condition shown in Fig. 2 and with the parts in the position shown in Fig. 2, contact 32 engages its cooperating contact 20, and contact 34 engages its cooperating contact 22. By means later to be described, thermostatic sub-assembly 29, which includes shank 36, head 38, thermostatic element 30 and cup-shaped member 42, may be forcibly disposed in the position shown in Fig. 2 and may be released by said means to permit movement of thermostat sub-assembly 29 to the position shown in Fig. 5. Substantial rotation of thermostatic element 30 about shank 36 is prevented by engagement of the distal portions of element 30 with the respective, relative adjacent surfaces of base member 4.

Base member or cover member 6 includes end walls 50, 50 and side walls 52, 52 which interfit with end walls 10, 10 and side walls 8, 8, respectively, of base member 4. Base members 4 and 6 may be secured together by conventional means such as headed screws 55. End walls 50, 50 provide overhanging portions 54, 54, respectively, for a purpose later to become apparent.

Movable means are carried by cover member 6 for cooperation with thermostatic sub-assembly 29 to effect movement of thermostatic element 30 between the respective positions shown in Figs. 2 and 5. An aperture 56 is provided in cover member 6 through which the handle 58 of this movable means projects outwardly to the exterior of the device. Handle 58 is integral with and forms a portion of movable supporting member 60. Supporting member 60 is mounted on base member 6 for pivotal movement about an axis by means of axially extending bearing portions 62 and 64 which are slidably mounted in cylindrical apertures 66 and 68, respectively. As best shown in Fig. 3, the surfaces of cylindrical apertures 66 and 68 act as bearing supports for the portions of the supporting member disposed therein.

Supporting member 60 provides an internally threaded aperture 70 which preferably is substantially aligned or coaxial with cup-shaped member 42 when the parts are in the relative position shown in Fig. 2. An externally threaded member, in this case an adjusting screw 72, is threaded into aperture 70. At one end of adjusting screw 72 is a cam 76 which cooperates with cam 39 and catch 40 when supporting means 60 is pivoted from the position shown in Fig. 5 to that shown in Fig. 2. It is apparent that adjusting screw 72 is adjustable along aperture 70 by merely rotating member 72 relative to support 60. Means such as a screw driver may be inserted through aperture 56 and into engagement with slot 78 in adjusting screw 72 for rotating it relative to supporting means 60. In this manner, adjusting screw 72 is accessible from the exterior of the device for adjustment of this member along support 60 and transversely with respect to the axis about which support 60 pivots.

Supporting means 60 provides a socket 82 in which one end of a compression coil spring 84 is seated. The opposite end of coil spring 84 is seated in a socket 86 provided by cover member 6. Coil spring 84 resiliently biases supporting member 60 for movement from the relative position shown in Fig. 2 to the retracted position shown in Fig. 5.

In operation, supporting means 60 may be disposed in the fully counterclockwise position shown in Fig. 5, which position is defined by engagement of handle 58 with the relatively adjacent portion of cover member 6. During movement of supporting member 60 from the position

shown in Fig. 5 to the position shown in Fig. 2, cam 76 at the end of member 72 moves into engagement with cooperating cam 39 provided by head 38. Continued movement of supporting member 60 in the clockwise direction is effective to move thermostatic sub-assembly 29 downwardly to the reset position shown in Fig. 2. At the position shown in Fig. 2, cam 76 has moved past cam 39 and into engagement with the catch formed by depression 40. Preferably, thermostatic element 30 is flexed by the pressure of cam 76 against head 38 when in the position shown in Fig. 2 to effect adjustment of element 30 as is well-known in the art, whereby creep of contacts 32 and 34 may be eliminated, and the desired operating temperature of the element is set. Although thermostatic element 30 is biased upwardly due to this mechanical flexure and by coil spring 46, and although supporting member 60 is biased in the counterclockwise direction by spring 84, the shape and arrangement of cam 76 and depression 40 is such that the parts will maintain themselves in the position shown in Fig. 2. In this position the contacts are closed. The contacts may be opened manually by simply moving handle 58 forcibly in a counterclockwise direction as viewed in Fig. 2 to the retracted position shown in Fig. 5 whereby sub-assembly 29, which includes thermostatic element 30, moves upwardly under the bias of element 30 and spring 46 to the position shown in Fig. 5 at which the contacts are mutually separated. Alternatively, with the parts in the position shown in Fig. 2, thermostatic element 30 is responsive to temperature change, such as that which might be occasioned by a current overload passing through element 30, whereby thermostatic element 30 would snap from the downwardly bowed shape or condition shown in Fig. 2 to an upwardly bowed shape or condition at which contacts 32 and 34 would be biased in a direction from engaged to disengaged relation with contacts 20 and 22, respectively. The result of this bias in the environment shown in Figs. 1-5 is that contacts 32 and 34 will be disengaged from contacts 20 and 22, respectively. At the point of snap of thermostatic element 30 from the downwardly bowed to the upwardly bowed shape, the upward bias of thermostatic element 30 due to the mechanical flexure thereof is released whereby catch 40 releases cam 76 and spring 84 is effective to pivot supporting member 60 in the counterclockwise direction as viewed in Fig. 2. Cam 76 having pivoted away from head 38, thermostatic sub-assembly 29 moves upwardly in its upwardly bowed shape or condition to the relative position shown in Fig. 5. With sub-assembly 29 in the position shown in Fig. 5 and with element 30 in its upwardly bowed condition, over-hanging portions 54, 54 engage the distal portions of element 30 and thereby act as stops to limit upward movement of these distal portions.

After thermostatic element 30 snaps from the shape or condition shown in Figs. 2 and 5 to the above-described upwardly bowed shape or condition, contacts 32 and 34 will be mutually separated from contacts 20 and 22, respectively, in the environment shown in Figs. 1-5, regardless of the pivotal position of supporting member 60. That is, even if supporting member 60 were pivoted from the position shown in Fig. 5 to that shown in Fig. 2 while the thermostatic element was in its upwardly bowed shape or condition (as indicated by the dotted-line shape of thermostatic element 30 in Fig. 2), neither of contacts 32 nor 34 would move into engagement with its respective cooperating contact. However, although contacts 32 and 34 (with supporting member 60 in its fully clockwise position as shown in Fig. 2) will be separated from their respective cooperating contacts when thermostatic element 30 has snapped to said upwardly bowed shape, contacts 32 and 34 will be engaged with their respective cooperating contacts when supporting member 60 is in its fully clockwise position

and thermostatic element 30 has snapped from the above-described, upwardly bowed condition to the downwardly bowed shape or condition shown in full lines in Fig. 2.

Accordingly, thermostatic element 30 along with the other parts of sub-assembly 29, is biased for movement along a path from a first position to a second position with respect to contacts 20 and 22 whereby in said first position the thermostatic means, when it responds to temperature change to change its shape, biases contacts 32 and 34 in a direction from engaging to disengaging position with respect to contacts 20 and 22, respectively. It will be noted that this embodiment and the embodiment shown in Figs. 7-10, whether or not modified as described herein, are trip-free. That is, even if handle 58 should be held in the position shown in Fig. 2, the snap of the thermostatic element in response to temperature change from its downwardly bowed condition to its upwardly bowed condition is effective to separate contacts 32 and 34 from contacts 20 and 22, respectively. Also, it will be noted that each of contacts 32 and 34 is disengaged from contacts 20 and 22, respectively, when thermostatic element 30 is disposed in the position and environment shown in Fig. 5 regardless of whether thermostatic element 30 is in the downwardly bowed shape or condition shown in Figs. 2 and 5 or in the upwardly bowed shape or condition described above.

It will be clear that the extent of movement of thermostatic element 30, as well as the amount of "pull-in" of thermostatic element 30, effected by pivotal movement of the supporting member from the position shown in Fig. 5 to that shown in Fig. 2 is determined by the adjustment of member 72 transversely of the pivotal axis of supporting member 60 and along supporting member 60. With supporting member 60 in the position shown in Fig. 2, the adjustable position of member 72 can be quickly, easily and accurately set.

Fig. 6 shows a member 90 which may be substituted for member 72 in the embodiment shown in Figs. 1-5. Member 90 may be substantially identical with member 72 except for the end thereof which provides the cam means for cooperation with cam 39 and depression 40. In this regard member 90 provides at one end a socket 92 which receives a cam in the form of a spherical ball 94. Ball 94 may be retained in socket 92 by spinning or otherwise turning in the end of member 92 at 96 in such manner that the ball can rotate freely.

Referring to the embodiment shown in Figs. 7-10 and 13, a base or casing 100 is shown which includes an open-ended base member 101. Base member 101 is hollow and provides internal surfaces closely fitting the sub-assembly 102 shown in Fig. 10. Subassembly 102 includes two electrically conductive terminals 104 and 106 which closely interfit with apertures 105 and 107, respectively, in base member 101 and which mount electrical contacts 108 and 110, respectively. Terminals 104 and 106 are fixedly secured to a base member 112 in any suitable manner. Base member 112 is formed of a suitable electrically insulating material and provides a boss 113 having socket 114 therein in which a bushing 116 is fixedly mounted.

A thermostatic sub-assembly 118, which is or may be identical with thermostatic sub-assembly 29 as described with respect to the embodiment shown in Figs. 1 through 5, is mounted for movement with respect to base member 112 in the same manner as sub-assembly 29 is mounted for movement with respect to base member 4. That is, head 120, shank 122, thermostatic element 124, and cup-shaped member 126 may be of the same form and construction as the corresponding parts in the embodiment shown in Figs. 1-5; and cup-shaped member 126 may be mounted telescopically in bushing 116 and confined for movement therein. Substantial rotation of thermostatic element 124 about shank 122 is prevented by engagement of the distal portions of element 124 with the respective, relatively

adjacent surfaces 127, 127 of base member 112. Electrical contacts 128 and 130 are carried by thermostatic element 124 for cooperating with contacts 108 and 110, respectively. A compression coil spring 132 has one end disposed against base member 112 and the other end seated in cup-shaped member 126 to resiliently bias sub-assembly 118 upwardly as viewed in Figs. 7 and 8. Head 120 provides a cam surface 136 and a catch 138 in the same manner as that provided by head 38 in the previously-described embodiment.

The open end of base member 101 may be substantially closed by a closure member 140. Member 140 may be secured to base member 101 by means such as screws 142. Slidably mounted in an aperture 144 in member 140 is a manually engageable, push-pull member 146. One leg 148, of a supporting means 149 in the form of an L-shaped member, is interlocked with a projection 150 secured to member 146. The other leg 152 of L-shaped member 149 is disposed in slidably, interfitting relationship with a substantially straight guideway provided by recesses 153, 153 in base member 101. Accordingly, member 146 and legs 152 and 148 are mounted for rectilinear movement on and with respect to base 100.

Leg 152 provides an internally threaded aperture 154 therein. Threadedly engaged in aperture 154 is a member 156. Member 156 mounts a cam member 158 at one end thereof. Member 156 with cam 158 may be of the same form and construction as member 90 with cam 94 thereon as shown in Fig. 6. Alternatively, member 156 and cam 158 could be eliminated and member 72 with cam 76 from the embodiment shown in Figs. 1-5 could be substituted therefor. In either event, a lock nut 159 may be tightened down on the projecting portion of member 156, or its substitute as the case may be, positively to lock that member rotationally with respect to leg 152. An aperture 160 is provided by base member 101 such that with the parts in the position shown in Fig. 7, lock nut 159 and member 154 are accessible from the exterior of the device. Accordingly, the position of member 156 with respect to leg 152 may be adjusted thereby to adjust member 156 along leg 152 and transversely of the path of rectilinear movement of leg 152.

A coiled compression spring 162 has one end seated in a socket 164 provided by base member 101 and has its other end disposed against the relatively adjacent end of leg 152. Spring 162 resiliently biases leg 152 and the structure fixed with respect thereto, for movement from the position shown in Fig. 7 to the retracted position shown in Fig. 8.

Fixed with respect to closure member 140 is an externally threaded portion 166. Figs. 7 and 8 illustrate the manner in which the switch may be mounted with portion 166 disposed in an aperture 168 in a panel or partition 170. In this regard, a nut 172 in threaded engagement with portion 166 may be disposed against one side of panel 170, and a lock nut 174 may be tightened down in threaded engagement with portion 166 and against the other side of panel 170.

In operation, member 146 is manually engageable and movable to the position shown in Fig. 7. During this movement cam 158 moves into engagement with cam 136 to move thermostatic sub-assembly 118 toward contacts 108 and 110. This movement brings contacts 128 and 130 into engagement with contacts 108 and 110, respectively, and continued movement of member 146 is effective to dispose cam 158 in catch 138 as shown in Fig. 7. In the position shown in Fig. 7 sub-assembly 118 is resiliently urged in a direction away from contacts 108 and 110 due to the mechanical flexure of thermostatic element 124 and due to compression spring 132. Leg 152 is resiliently urged to the right as viewed in Fig. 7 by compression spring 162. However, the shape and relative arrangement of cam 158 and catch 138 are such as to maintain the parts in the position shown in Fig.

7. L-shaped member 149 can be forcibly retracted to the position shown in Fig. 8 whereby cam 158 will be released from catch 138 to permit thermostatic sub-assembly 118 to move from the position shown in Fig. 7 to the position shown in Fig. 8 under the bias of element 124 and spring 132. Also, thermostatic element 124 is snappable, in response to temperature change, from the downwardly bowed shape or condition shown in Figs. 7 and 8 to an upwardly bowed shape or condition as described with respect to the Figs. 1-5 embodiment. When thermostatic element 124 snaps to this upwardly bowed condition, thermostatic element 124 resiliently biases contacts 128 and 130 in a direction away from contacts 108 and 110, respectively, and the resilient bias due to mechanical flexure of the thermostatic element is released permitting cam 158 to be released from catch 138. When cam 158 is released from catch 138, L-shaped member 149 moves to the retracted position shown in Fig. 8 under the bias of compression spring 162. As with the embodiment shown in Figs. 1-5, when thermostatic element 124 is in the position shown in Fig. 7, contacts 128 and 130 will be in engagement with contacts 108 and 110, respectively, so long as the thermostatic element remains in the downwardly bowed shape or condition shown in Figs. 7 and 8. However, and as clearly illustrated in Fig. 13, when thermostatic element 124 is in the above-described upwardly bowed shape or condition and in the environment shown in Figs. 7-9 and 13, contacts 128 and 130 will remain out of engagement with contacts 108 and 110 regardless of whether the thermostatic sub-assembly is in the position shown in Fig. 7 or the position shown in Fig. 8. Accordingly, referring to Fig. 13 it will be apparent that with the parts in the environment shown in Figs. 7-9 and after thermostatic element 124 has snapped to the upwardly bowed condition in response to a temperature change, contacts 128 and 130 will remain out of engagement with contacts 108 and 110 even though supporting member 149 has moved to the position shown in Fig. 7.

Upstanding portions 178 and 180 may be provided in fixed relation to base member 112 as shown in Figs. 7, 8 and 10. Portions 178 and 180 are preferably integral with base 112 and are also formed of electrically insulating material. These portions act as barriers to prevent the possibility of an arc occurring between thermostatic element 124 and either of contacts 108 and 110.

Fig. 11 illustrates a portion of a modified form of thermostatic sub-assembly which may be substituted for that shown in both of the above-described embodiments. For the purposes of this description, this modified sub-assembly has been shown in Fig. 11 as having been incorporated into the embodiment of Figs. 7-10. According to this modified form, thermostatic sub-assembly 181 includes a thermostatic element 182 which is or may be identical with the thermostatic element included in both of the above-described embodiments. In this regard thermostatic element 182 provides an aperture 184 located substantially centrally thereof and extending through thermostatic element 182 from one side thereof to the other. Thermostatic sub-assembly 181 further includes a shank 186 disposed in aperture 184 and extending within bushing 116. A compression coil spring 188 is disposed about shank 186 and within bushing 116. One end of coil spring 188 is disposed against base member 101 and the other end thereof is disposed against one side of thermostatic element 182. A head 190 is fixedly carried by shank 186. The lower portion of head 190 is engageable with the side of thermostatic element 182 opposite from that engaged by one end of spring 188. Another portion of head 190 provides a cam surface 192 for cooperation with cam 158 and socket or catch 194. Bushing 116, in cooperation with spring 188 and shank 186, guides thermostatic element 182 in its path of movement between the above-described relative positions. It will be apparent that thermostatic sub-assembly

8
sembly 181 functions in substantially the same manner and provides substantially the same advantages as that attributed above with respect to the thermostatic sub-assembly incorporated in the embodiments shown in Figs. 1-5 and 7-10.

In Fig. 12, another thermostatic sub-assembly 200 is shown which may be substituted for thermostatic sub-assembly 29 in the embodiment shown in Figs. 1-5. Thermostatic sub-assembly 200 includes a thermostatic element 202 which is or may be identical with the thermostatic element included in both of the above-described embodiments. In this regard thermostatic element 200 provides an aperture 204 located substantially centrally thereof and extending through this element from one side thereof to the other. Thermostatic sub-assembly 200 further includes a generally cup-shaped member 206. Integral with cup-shaped member 206 or otherwise secured thereto, is a member 207 which provides a shank 208 extending between shoulder 209 and flange 210. As is apparent from Fig. 12, shank 208 is disposed within aperture 204 provided by thermostatic element 202, the latter being carried on the member 207 between the said flanges. Alternatively, it will be obvious that thermostatic element 202 may be mounted in like manner on member 207 between flange 210 and the adjacent portion of cup-shaped member 206. A shank 212 fixedly carries a head 214. Head 214 provides a cam or cam surface 216 and a catch 218. Shank 212 threadedly engages a complementary threaded aperture 220 in cup-shaped member 206 and member 207. Cup-shaped member 206 is slidably received in and guided for movement by bushing 28 which is fixedly supported by base member 4'. Thermostatic sub-assembly 200 is biased upwardly as viewed in Fig. 12 by spring 46. It will be noted that base member 4', as shown in Fig. 12, is or may be substantially identical with base member 4 as shown in Fig. 5 except that in the modification shown in Fig. 12, an aperture 222 is provided in base member 4' in substantial alignment with threaded shank 212. It will be seen that threaded shank 212 is accessible from the exterior of the device whereby a tool such as a screw driver may be inserted through aperture 222 to engage a slot 224. In this manner head 214 is adjustable along its supporting means and transversely with respect to the axis about which support 60 of this embodiment pivots. By this means the extent of movement of the thermostatic sub-assembly from the position shown in Fig. 5 to the position shown in Fig. 2, and, concomitantly therewith, the pull-in of the thermostatic element, may be adjusted.

It will be clear that if the modified sub-assembly shown in Fig. 12 were substituted for that shown in Figs. 1-5, member 72 could be formed integral with or otherwise non-adjustably fixed with respect to supporting means 60.

55. Since the cam member, which is movably mounted by the supporting means of each of the above-described embodiments and modifications, coacts with the head of the thermostatic sub-assembly to move that sub-assembly toward the respective fixed contacts rather than by direct engagement of the cam member with the thermostatic element, wear on the thermostatic element is reduced and localized deformation of this element is avoided. Furthermore, by means of the head disposed intermediate the thermostatic element and the cam-providing member movably mounted by the supporting means, the translation of forces from the supporting means to the thermostatic element is improved since the resultant forces acting on this element are substantially aligned with the path of movement thereof.

75. Obviously, the size, shape and other characteristics of the catch which engages and retains the cam carried by the supporting member are limited when the catch is provided by the thermostatic element as in the above-cited patent to J. D. Bolesky since any change in the size and/or shape of this catch alters the characteristics

of the thermostatic element. In contradistinction thereto, the size and shape of the catch as provided by the above-described intermediate member can be altered as desired to provide optimum shock and vibration resistance as well as other characteristics without modifying or affecting the characteristics of the thermostatic element.

It is noted that it would be a simple matter to modify the shape of the cooperating cams in each of the above-described embodiments and modifications to provide the desired relative type and/or rate of movement of the thermostatic subassembly from the position shown in Figs. 5 or 8 to the position shown in Figs. 2 or 7, respectively. For example, this movement could be relatively slow, relatively rapid or otherwise, as desired.

The environment of the snap-acting element of each of the embodiments set forth in this description may be altered, if desired, by providing the particular embodiment with an auxiliary heater and/or a slotted, resilient, metallic plate in the manner clearly set forth in Fig. 9 in Figs. 12-15, respectively, of the patent to J. D. Bolesky referred to above.

In view of the above, it will be seen that the several objects of the invention are achieved and other advantageous results attained.

As many changes could be made in the above constructions without departing from the scope of the invention, it is intended that all matter contained in the above description or shown in the accompanying drawings, shall be interpreted as illustrative and not in a limiting sense.

We claim:

1. A device comprising a first electrical contact and a second electrical contact, a snap-acting thermostatic element responsive to temperature change, said thermostatic element carrying said first contact, means biasing said thermostatic element for movement along a path from a first position to a second position with respect to said second contact whereby in said first position the thermostatic element, when it responds to said temperature change, biases said first contact in a direction from engaging to disengaging position with respect to said second contact; said first contact, with said thermostatic element in said second position, being disengaged from said second contact; additional means operatively associated with said thermostatic element for moving said element from said second position to said first position and for retention of said element in said first position until released, said additional means including a member accessible from the exterior of the device for adjustment of the extent of movement of the thermostatic element from said second position to said first position.

2. A device comprising a first electrical contact and a second electrical contact, a snap-acting thermostatic element responsive to temperature change, said thermostatic element carrying said first contact, means biasing said thermostatic element for movement along a path from a first position to a second position with respect to said second contact whereby in said first position the thermostatic element, when it responds to said temperature change, biases said first contact in a direction from engaging to disengaging position with respect to said second contact; said first contact, with said thermostatic element in said second position, being disengaged from said second contact; additional means operatively associated with said thermostatic element for movement of said element from said second position to said first position and for retention of said element in said first position until released, said additional means including supporting means movable with respect to said thermostatic element and means guided for movement along said path, said supporting means carrying a member in threaded engagement therewith, said last-named means being engageable with said thermostatic element and with said member for moving said element along said path from said second position to said first position in response to corresponding

movement of said supporting means, and said member being accessible from the exterior of the device for adjustment of the extent of movement of the thermostatic element from said second position to said first position.

3. A device comprising a first electrical contact and a second electrical contact, a snap-acting thermostatic element responsive to temperature change, said thermostatic element carrying said first contact, means biasing said thermostatic element for movement along a path from a first position to a second position with respect to said second contact whereby in said first position the thermostatic element, when it responds to said temperature change, biases said first contact in a direction from engaging to disengaging position with respect to said second contact; said first contact, with said thermostatic element in said second position, being disengaged from said second contact; additional means operatively associated with said thermostatic element for movement of said element from said second position to said first position and for retention of said element in said first position until released, said additional means including a first member movable with respect to said thermostatic element, said additional means further including means guided for movement along said path, said last-named means including a second member threadedly engaging a third member, said third member being engageable with said first member and with said thermostatic element for moving said element along said path from said second position to said first position in response to corresponding movement of said first member, said third member being accessible from the exterior of the device for adjustment of said third member with respect to said second member to adjust the extent of movement of the thermostatic element from said second position to said first position.

4. A device comprising a first electrical contact and a second electrical contact, snap-acting thermostatic means responsive to temperature change, said thermostatic means carrying said first contact, means biasing said thermostatic means for movement along a path from a first position to a second position with respect to said second contact whereby in said first position the thermostatic means, when it responds to said temperature change biases said first contact in a direction from engaging to disengaging position with respect to said second contact; said first contact, with said thermostatic means in said second position, being disengaged from said second contact; means guided for movement along said path and engageable with said thermostatic means; said last-named means including a member providing a cam surface and a catch; and additional means movable with respect to said thermostatic means and engageable first with said cam surface for moving said thermostatic means along said path from said second position to said first position and then with said catch for retaining said thermostatic means in said first position until released.

5. A device comprising a base, a first electrical contact, a second electrical contact mounted on said base, a snap-acting thermostatic element carrying said first contact and being provided with an aperture extending between opposite sides thereof, said thermostatic element being responsive to temperature change to change its shape, means biasing said thermostatic element from a first position to a second position with respect to said second contact whereby in said first position the thermostatic element, when it responds to said temperature change, biases said first contact in a direction from engaging to disengaging position with respect to said second contact; said first contact, with said thermostatic element in said second position, being disengaged from said second contact; a shank disposed loosely in the aperture in said thermostatic element and having a head fixed with respect thereto, means movable relative to said thermostatic element, said head being engageable with one side of said thermostatic element, said biasing means comprising a coil spring co-

axial with said shank, one end of said spring being engageable with said base, and the other end of said spring abutting said thermostatic element to urge it against said head, and said head providing a surface for cooperation with said last-named means to move said thermostatic element from said second position to said first position and to retain said thermostatic element in said first position until released.

6. A device comprising a base, a first electrical contact, a second electrical contact mounted on said base, a snap-acting thermostatic element carrying said first contact and being provided with an aperture extending between opposite sides thereof, said thermostatic element being responsive to temperature change, means biasing said thermostatic element from a first position to a second position with respect to said second contact whereby in said first position the thermostatic element, when it responds to said temperature change, biases said first contact in a direction from engaging to disengaging position with respect to said second contact; said first contact, with said thermostatic element in said second position, being disengaged from said second contact; a shank disposed loosely in the aperture in said thermostatic element and having a head fixed with respect thereto, means movable relative to said thermostatic element, said head being engageable with one side of said thermostatic element; a cup-shaped member fixed with respect to said shank at the opposite side of said thermostatic element, said biasing means comprising a spring having one end seated in said cup-shaped member and the other end abutting said base member, and said head providing a surface for cooperation with said relatively movable means to move said thermostatic element from said second position to said first position.

7. A device comprising a base, a first electrical contact, a second electrical contact mounted on said base, snap-acting thermostatic means carrying said first contact and being responsive to temperature change to change its shape, spring means engageable with said base and biasing said thermostatic means for movement from a first position to a second position with respect to said second contact whereby in said first position the thermostatic means when it responds to said temperature change, biases said first contact in a direction from engaging to disengaging position with respect to said second contact; said first contact, with said thermostatic means in said second position, being disengaged from said second contact; supporting means mounted on said base for movement with respect to said thermostatic means, a member carried by said supporting means and providing a first cam surface; means including two portions fixed with respect to each other, one of said portions being adapted to abut said thermostatic means, the other of said portions presenting a second cam surface for cooperation with said first cam surface whereby said thermostatic means is moved from said second position to said first position in response to movement of said supporting means, said last-named means providing a catch adjacent said second cam surface for retaining said member to maintain said thermostatic means in said first position until said member is forcibly retracted or until said thermostatic means responds to said temperature change; and means engageable with said base and biasing said supporting means for movement of said member to retracted position when said thermostatic means responds to said temperature change.

8. A device comprising a base, a first electrical contact, a second electrical contact mounted on said base, snap-acting thermostatic means carrying said first contact and being responsive to temperature change to change its shape, spring means engageable with said base and biasing said thermostatic means for movement from a first position to a second position with respect to said second contact whereby in said first position the thermostatic means,

tion the thermostatic means when it responds to said temperature change, biases said first contact in a direction from engaging to disengaging position with respect to said second contact; said first contact, with said thermostatic means in said second position, being disengaged from said second contact; supporting means mounted on said base for movement with respect to said thermostatic means, a member carried by said supporting means and providing a first cam surface; means including two portions fixed with respect to each other, one of said portions being adapted to abut said thermostatic means, the other of said portions presenting a second cam surface for cooperation with said first cam surface whereby said thermostatic means is moved from said second position to said first position in response to movement of said supporting means, said last-named means providing a catch adjacent said second cam surface for retaining said member to maintain said thermostatic means in said first position until said member is forcibly retracted or until said thermostatic means responds to said temperature change; and means engageable with said base and biasing said supporting means for movement of said member to retracted position when said thermostatic means responds to said temperature change, said member threadedly engaging said supporting means and said member being accessible from the exterior of the device for adjustment of said member along said supporting means.

9. A device comprising a base, a first electrical contact, a second electrical contact mounted on said base, snap-acting thermostatic means carrying said first contact and being responsive to temperature change to change its shape, spring means engageable with said base and biasing said thermostatic means for movement from a first position to a second position with respect to said second contact whereby in said first position the thermostatic means when it responds to said temperature change, biases said first contact in a direction from engaging to disengaging position with respect to said second contact; said first contact, with said thermostatic means in said second position, being disengaged from said second contact; supporting means mounted on said base for movement with respect to said thermostatic means, a member carried by said supporting means and providing a first cam surface; means including two portions fixed with respect to each other, one of said portions being adapted to abut said thermostatic means, the other of said portions presenting a second cam surface for cooperation with said first cam surface whereby said thermostatic means is moved from said second position to said first position in response to movement of said supporting means, said last-named means providing a catch adjacent said second cam surface for retaining said member to maintain said thermostatic means in said first position until said member is forcibly retracted or until said thermostatic means responds to said temperature change; and means engageable with said base and biasing said supporting means for movement of said member to retracted position when said thermostatic means responds to said temperature change, said other portion being being adjustably fixed in threaded engagement with said one portion and being accessible from the exterior of the device for adjustment thereof with respect to said one portion.

10. A device comprising a base, a first electrical contact, a second electrical contact mounted on said base, snap-acting thermostatic means carrying said first contact and being responsive to temperature change, spring means engageable with said base and biasing said thermostatic means for movement from a first position to a second position with respect to said second contact whereby in said first position the thermostatic means, when it responds to said temperature change, biases said first contact in a direction from engaging to disengaging position with respect to said second contact; said first con-

tact, with said thermostatic means in said second position, being disengaged from said second contact; supporting means mounted on said base for pivotal movement about an axis, a member carried by said supporting means and having a first cam surface at one end; means including two portions fixed with respect to each other, one of said portions being adapted to abut said thermostatic means, the other of said portions presenting a second cam surface for cooperation with said first cam surface whereby said thermostatic means is moved from said second position to said first position in response to pivotal movement of said supporting means, said last-named means providing a catch adjacent said second cam surface for retaining said member to maintain said thermostatic means in said first position until said member is forcibly retracted or until said thermostatic means responds to said temperature change; and means engageable with said base and biasing said supporting means for pivotal movement of said member to retracted position when said thermostatic means responds to said temperature change.

11. A device comprising a base, a first electrical contact, a second electrical contact mounted on said base, snap-acting thermostatic means carrying said first contact and being responsive to temperature change, spring means engageable with said base and biasing said thermostatic means for movement from a first position to a second position with respect to said second contact whereby in said first position thermostatic means, when it responds to said temperature change, biases said first contact in a direction from engaging to disengaging position with respect to said second contact; said first contact, with said thermostatic means in said second position, being disengaged from said second contact; supporting means slidably mounted on said base for rectilinear movement along a path lying transversely with respect

25

30

35

to the path of movement of said thermostatic means between said first and second positions, a member carried by said supporting means and having a first cam surface at one end, means including two portions fixed with respect to each other, one of said portions being adapted to abut said thermostatic means, the other of said portions presenting a second cam surface for cooperation with said first cam surface whereby said thermostatic means is moved from said second position to said first position in response to rectilinear movement of said supporting means, said last-named means providing a catch adjacent said second cam surface for retaining said member to maintain said thermostatic means in said first position until said member is forcibly retracted or until said thermostatic means responds to said temperature change; and means engageable with said base and biasing said supporting means for rectilinear movement of said member to retracted position when said thermostatic means responds to said temperature change.

12. The device as set forth in claim 2 wherein said member provides a socket and includes a rotatable spherical ball retained within said socket whereby said ball comprises the portion of said member engageable with said last-named means.

UNITED STATES PATENT OFFICE
CERTIFICATE OF CORRECTION

Patent No. 2,863,965

December 9, 1958

Wilfred W. Cardin et al.

It is hereby certified that error appears in the printed specification of the above numbered patent requiring correction and that the said Letters Patent should read as corrected below.

Column 2, line 24, for "drawings" read -- drawing --; column 3, lines 21 and 22, for "relative" read -- relatively --; column 6, line 3, for "cooperating" read -- cooperation --; column 11, line 62, for "siad" read -- said --; column 13, line 29, after "position" insert -- the --.

Signed and sealed this 26th day of April 1960.
